UNITED STATES PATENT OFFICE.

REIMER N. DITHMER, OF CHICAGO, ILLINOIS.

FISHPLATE FOR RAILWAY RAILS.

1,422,187.

Specification of Letters Patent. Patented July 11, 1922.

Application filed August 29, 1921. Serial No. 496,455.

To all whom it may concern:

Be it known that I, REIMER N. DITHMER, a citizen of the United States, and a resident of the city of Chicago, county of Cook, 5 and State of Illinois, have invented certain new and useful Improvements in Fishplates for Railway Rails, of which the following is a specification.

This invention relates to fish plates for 10 railway rails, which provide a rigid joint, and which will be unaffected by so-called "creeping" of such rails.

Other objects will appear hereinafter.

The invention consists in the combinations and arrangements of parts hereinafter described and claimed.

The invention will be best understood by reference to the accompanying drawings forming a part of this specification, and in 20 which,—

Fig. 1 is a top plan view of adjoining ends of rails showing the fish plates applied thereto,

Fig. 2 is a side elevation of the invention 25 in operative position,

Fig. 3 is a bottom view of the plate showing the interlocking tongues and grooves,

Fig. 4 is a section on the line 4—4, Fig. 2, and

Fig. 5 is a bottom view of one length of fish plate.

Railway rails are ordinarily joined by fish plates which are held in position by spikes driven into the ties. Plates of this 35 type become loosened by creeping of the rails and fail to retain the rails in proper position. My invention provides fish plates which are unaffected by creeping of the rails and which provide a rigid joint, thus obviating undesirable sinking of the rails at 40 their adjoining ends.

The invention consists of rolled steel plates of the type shown in Fig. 5, and as 45 many similar plates may be formed in a continuous strip as desired, being then cut to any desired length. As shown, each of such plates has a base 1, preferably having tongues 2 and slots 3, the base member being adapted to extend under the rails 4 a 50 suitable distance. The wall of the plate rises outwardly, upwardly, and inwardly, as shown at 5, Fig. 4, forming an interior groove 6, in which the flanges 7 of the rails

4 are snugly engaged, such wall terminating in a flat portion 8 which lies against the 55 webs 9 of the rails 4. A plate is provided on the opposite side of the rails which is identical to the plate described, except that the same is reversed in position so that the tongues 2 engage in the slots 3 of each of 60 the plates so as to interlock when the plates are slid longitudinally with respect to each other. The bottoms of the plates have a thickened portion 10 adapted to engage a groove provided in the tie to prevent lateral 65 shifting of the plates. I preferably form the plates so that the base has the greatest thickness, the wall 5 being next in thickness, and the flat portion 8 having the least thickness. 70

Set screws 11 are tapped through the upper side of the portions 5 as shown, and engage the flanges 7 of the rails 4 to hold the same rigidly against vertical movement with respect to each other and lock said 75 plates in position. The plates are provided with suitable bores corresponding to bores in the webs of the rails, through which bolts 12 are passed, such bolts being secured in position by nuts 13. 80

The interlocking portions of the plates together with the grooves 6, set screws 11, and bolts 12 hold the rail ends rigidly against vertical and longitudinal movement with respect to each other and at the same 85 time the joint is free to move during creeping of the rails, being unaffected in efficiency thereby.

While I have illustrated and described the preferred form of construction for carrying 90 my invention into effect, this is capable of variation and modification without departing from the spirit of the invention. I, therefore, do not wish to be limited to the precise details of the construction set forth, 95 but desire to avail myself of such variations and modifications as come within the scope of the appended claim.

Having described my invention, what I claim as new and desire to secure by Letters Patent, is:—

In a joint for rails comprising sections having slidably detachable interlocking bottoms and extending over and forming slots for flanges of said rails, said interlocking 105 bottoms being thickened and together form-

ing a rib adapted to prevent lateral movement of said joint; and means extending into said slots for adjustably engaging said flanges to prevent accidental detachment of 5 said interlocking bottoms and to compensate for play in said slots.

In testimony whereof I have signed my

name to this specification in the presence of two subscribing witnesses.

REIMER N. DITHMER.
